UNITED STATES PATENT OFFICE.

OWEN DAVID LUCAS, OF BAYSWATER, LONDON, ENGLAND.

CARBURETER FOR INTERNAL-COMBUSTION ENGINES.

1,082,466.

Specification of Letters Patent. Patented Dec. 23, 1913.

Application filed June 3, 1913. Serial No. 771,471.

To all whom it may concern:

Be it known that I, OWEN DAVID LUCAS, a subject of His Majesty the King of England, residing at Bayswater, in the county 5 of London, Kingdom of England, have invented certain new and useful Improvements in Carbureters for Internal-Combustion Engines, of which the following is a specification.

10. This invention has reference to improvements in carbureters for internal combustion engines, and its object is to provide a more perfect mixture under all conditions of engine load and speed than has heretofore been 15 attained.

The invention has to do particularly with that type of carbureter described in my application filed on March 18, 1911, Serial No. 615,294, wherein there is provided a jet situated in a jet chamber, as distinguished from the mixing chamber proper, the jet chamber communicating with the mixing chamber by suitable orifices. In the carbureter of the aforesaid application the mixing chamber is exposed to the direct suction of the engine, there being no throttling means between the mixing chamber and engine, while the air supply is controlled by a mechanically variable port between the 25 mixing chamber and the atmosphere. The suction on the jet, and consequently the amount of hydrocarbon admitted to the mixing chamber, is in the structure shown in the aforesaid application controlled by a 30 mechanically variable port between the jet chamber and the atmosphere, the arrangement being such that if the effective area of the air port to the mixing chamber is being increased, that of the air port of the jet 35 chamber is being correspondingly diminished, and vice versa.

According to the present invention means are provided for controlling the suction of the jet by mechanically varying the size 40 of the orifice through which communication is had between the jet and mixing chambers and the arrangement is also such that when the effective area of the air port of the mixing chamber is being enlarged the orifice

between the jet and mixing chambers is increased in effective area, and vice versa, while the port between the jet chamber and the atmosphere remains constant. Again, the variable orifice between the jet and mixing chambers may be employed in a carbureter where the air ports of the jet and mixing chambers are simultaneously varied in effective area, but in the opposite sense one to the other, so that when the air port of the mixing chamber is increased in effective 50 area the orifice between the jet chamber and mixing chamber is also increased in effective area, while the air port between the jet chamber and the atmosphere is diminished in effective area, and vice versa. 55

The invention will be best understood from a consideration of the following detailed description taken in connection with the accompanying drawings forming a part of this specification, with the further understanding that while the drawings show a practical form of the invention, the latter is not confined to any strict conformity with the showing of the drawings but may be changed and modified so long as such 60 changes and modifications mark no material departure from the salient features of the invention. 65

In the drawings:—Figure 1 is a diagram illustrating the invention in its simplest 65 adaptation. Fig. 2 is a similar diagram illustrating the invention as embodied in a carbureter operating according to the aforesaid application.

Referring to the drawings there is shown 85 a carbureter provided with a mixing or secondary-air chamber *a* communicating with the atmosphere by an air port *c* and with the cylinder *k* of an engine by an induction pipe *r*. There is also provided a jet 90 or primary-air chamber *d* entered at the lower portion by a jet *j* which may be considered as fed by a constant level float feed device such as commonly employed in carbureters. The chamber *d* communicates directly with the atmosphere by way of a port *e* located at a point distant from the jet *j*. The port *c* is controlled as to area 95

by a throttle *f* which is simply indicated as a sliding throttle and may be arranged to either control the port *c* alone, as in Fig. 1, or to simultaneously and oppositely control the ports *c* and *e*, as in Fig. 2. The chambers *a* and *d* communicate through an orifice *l*, which may be either single or multiple, it being sometimes advisable to have the orifice *l* composed of a number of small passages, but in any event the area of the orifice *l*, whether single or multiple, is small or minute as compared with the ports *e* and *c*, and particularly the port *c*. In the structure shown in the aforesaid application this orifice is of constant area at all times, while the control of the suction of the jet is affected by a manipulation of the throttle common to the air ports of both the jet and mixing chambers.

In accordance with the present invention the suction of the jet is further controlled by a shutter *o* adapted to vary the effective area of the orifice *l* between the two chambers *d* and *e* and so arranged that when the port *c* is increased or diminished in effective area the orifice *l* will be varied in effective area in the same sense as the port *c*. In Fig. 1 the port *e* remains constant during the adjustments of the port *c* and orifice *l*. In Fig. 2 the port *c* and orifice *l* are increased or diminished in effective area in the same sense, while the port *e* is diminished in effective area as the port *c* and orifice *l* are increased in effective area, and is increased in effective area as the port *c* and orifice *l* are diminished in effective area. The movements of the two control shutters *f* and *o* may be caused in any suitable manner, and this may be brought about by any suitable operating means, such as indicated in the drawings, where there is shown a bell-crank lever *g*, pivoted at *h* and connected by links *i*, *i'*, to the shutters or valves *f* and *o*, respectively. An operating link *n* connected to the lever *g* may extend to any convenient point.

When the engine piston is moving on the suction stroke, subatmospheric conditions are produced within the chamber *a* and similar conditions are also produced in the chamber *d*, since these two chambers are in communication by way of the orifice *l*, and while both chambers may each be in communication with the atmosphere through the respective air ports *c* and *e* there are still such subatmospheric conditions in the chamber *d* that there is caused an inflow of fuel through the jet *j* and this is met by air, which may be termed primary air, entering the chamber *d* through the air port *e* and the primary air and fuel pass into the chamber *a* through the orifice *l* which is of controllable effective area where the diluting

or secondary air entering by way of the port *c* is met and a suitable mixture is effected. The air port of the chamber *a* is so situated that when it is decreased in effective area the degree of subatmospheric pressure in the chamber *a* caused by the suction of the engine tends to increase, wherefore a similar condition arises in the chamber *d* in the structure shown in Fig. 1 and this condition may be increased or diminished by varying the effective area of the orifice *l*. In the structure shown in Fig. 2 the air port of the jet or primary air chamber *d* is decreased in effective area as the air port to the chamber *a* is increased and vice versa, and while a decrease of the effective size of the air port *c* tends to increase the suction at the jet *j* this tendency is to an extent counteracted by the simultaneous opening of the port *e*, which under these circumstances becomes a jet controlling port. The action of the air port *c* and its throttle on the jet is opposite to the manner in which a throttle operates when it is placed, as is customary, in the suction pipe between the jet and the engine.

The action of the jet is modified by increasing or diminishing the effective area of the orifice *l* and increasing or diminishing of the effective area of the air port *c* both in the same sense, and under some circumstances the action is further modified by the decrease or enlargement of the effective area of the port *e* with the increase or decrease of the effective area of the port *c*, this is in the opposite sense thereto.

What is claimed is:—

1. A carbureter, for internal combustion engines, provided with two separate chambers, one chamber having means for free constant communication with the engine and also provided with an air port opening directly to the atmosphere, and the other chamber having an air port opening directly to the atmosphere and also having a fuel inlet in the lower portion thereof, said chambers being in direct communication through a small orifice located on substantially the level of the mouth of the jet, and said orifice and the air port of the first-named chamber being provided with throttling means for regulating their effective areas and movable in the same sense.

2. A carbureter, for internal combustion engines, provided with two separate chambers, one chamber having means for free constant communication with the engine and also provided with an air port opening directly to the atmosphere, and the other chamber having an air port opening directly to the atmosphere and also having a fuel inlet in the lower portion thereof, said chambers being in direct communication through

a small orifice located on substantially the level of the mouth of the jet, and said orifice and the air port of the first-named chamber being provided with throttling means for regulating their effective areas and movable in the same sense, the air port of the second-named chamber being also provided with throttling means movable in

the opposite sense to the movements of the first-named throttling means.

10

In testimony whereof I have signed this specification this 21st day of May 1913.

OWEN DAVID LUCAS.
